DESIGN FOR A FINGER RING OR SIMILAR ARTICLE

Aaron Elkonin, Brooklyn, N. Y.

Application December 7, 1942, Serial No. 108,957

Term of patent 14 years

To all whom it may concern:

Be it known that Aaron Elkonin, a citizen of no country, but having declared his intention of becoming a citizen of the United States, and resident of Brooklyn, in the county of Kings and State of New York, has invented a new, original, and ornamental Design for a Finger Ring or Similar Article, of which the following is a specification, reference being had to the accompanying drawing, forming part thereof, in which the figure is a side elevational view, slightly in perspective of a finger ring showing my new design, the

opposite side of which is the same as the side shown.

My design is characterized by the specific configuration and proportions of the surface ornamentation in association with a pebble background arranged on the shanks of a ring of the type shown.

I claim:

The ornamental design for a finger ring or similar article, substantially as shown and described.

AARON ELKONIN.
